UNITED STATES PATENT OFFICE.

EMIL JAHR, OF BERLIN, GERMANY.

INHALER.

SPECIFICATION forming part of Letters Patent No. 399,901, dated March 19, 1889.

Application filed June 13, 1888. Serial No. 277,020. (No model.)

To all whom it may concern:

Be it known that I, EMIL JAHR, Secretary at the German Government Board of Health of Berlin, in the Kingdom of Prussia and German Empire, have invented a new and useful Improved Inhaling Apparatus, of which the following is a specification, reference being had therein to the accompanying drawings.

This invention relates to an apparatus for conveying medicament into the human body by inhaling. In order to manage this, I use the apparatus shown in the accompanying drawings, in which—

Figure 1 is a side view of such an apparatus; Fig. 2, a top view; Fig. 3, a vertical cross-section through the line xx , Fig. 2; and Fig. 4 is a horizontal cross-section of the same.

In order to convey evaporated medicament into the human body by inhaling, and to deposit the same therein, it must be mixed with air of a temperature higher than that of the human body—namely, over 37° centigrade. The air must be completely saturated with steam and so inhaled.

The apparatus consists of a round or oval boiler, a , in which is placed the round or oval boiler b , and so formed that it stands at a certain distance from the side walls of the boiler a . The space between the two boilers a and b is closed at the top, but can be filled with water through a' in the top and run off at the cock a'' . The water is warmed to a temperature of 50° centigrade by means of the gas-burner c or other suitable way from under the boiler a . Between the bottom of the inner boiler, b , and the boiler a is a bent tube or pipe, d , placed, the one end of which passes out through the boiler a into the air at d' , while the other end is led into the boiler b at d'' . Opposite the opening d'' is a branch, b' , led into the side of the boiler b . The boiler b has a hinged cover or lid. The branch b' is for conducting the air, which is warmed in the boiler b , to the patient through the tube h . The branch b' passes through a branch, a'' , on the boiler a , between which there is a circular space. This space is kept warm, being in communication with the water in the boiler a . In this way is the warmed air which is drawn from the boiler b kept warm. Right or left on the boiler a are two sprays, e , of usual con-

struction, the cisterns of which, e' , are heated by gas or a spirit flame. The safety-valves of these cisterns are led into the boiler a . The mouth-piece of the sprays are conducted into the boiler b and lie over the suction-pipes e'' . The suction-pipes e'' are led into the well v in the boiler b . The well v is filled with the medicament which it is desired to be inhaled through the opening b^3 in the cover and eventually run off again by the pipe r and cock r' . Medicament which has been evaporated in another apparatus could also be led into the boiler b through the opening b^3 .

In order to ascertain the temperature and moisture of the air at any moment, and so arrange the burner under the boiler a and the cisterns e' , the boiler b is provided with two thermometers, $f f'$. The thermometer f tells the temperature of the air, and the thermometer f' , whose bulb is surrounded with gauze, rests in the box g , which contains water, and is kept continually moist, according to the moisture of the air and steam, and thus the moisture of the mixture can be ascertained.

In order that the thermometer f' should register correctly, there is a small "fly" in the boiler b , which is driven by clock-work on the cover, Figs. 1 and 2, which brings the air in contact with the bulb of the thermometer f' .

The working of the apparatus is as follows: On the branches a^2 b^2 is fastened an india-rubber tube, h , the free end of which the patient places to his mouth. The patient draws at each breath a portion of the air in from the boiler b , which is replaced by dried air from the spiral tube d , which enters at d' from outside and escapes at d'' into the boiler b , while the two sprays work continually, and thus keep the entering air moist with steam and charged with the medicament. The air entering the tube d can be passed through a holder, k , containing chloride of calcium when it is desirable or necessary to filter it from its moisture and warmth and to clear it. In the case that only gaseous medicament is used, then only is steam added to the same in the boiler b by the spray-pipes e .

What I claim, and desire to secure by Letters Patent of the United States, is—

In an inhaler, the combination of the water-boiler a , in which the air-reservoir b is

placed, with the spray-pipes e , and the double branch pipes $a^3 b^3$, with the india-rubber pipe h , arranged as described, whereby the air enters the spiral tube d , is warmed therein with steam and the desired medicament, and is finally drawn off through the double branch $a^3 b^3$, substantially as described.

In witness whereof I have hereunto set my hand in presence of two witnesses.

EMIL JAHR.
